[57] CLAIM

The ornamental design for a raised roof truck exterior surface, as shown and described.

DESCRIPTION

FIG. 1 is a perspective view of one embodiment of the exterior surface of a truck of the present invention; FIG. 2 is a right side view of the truck exterior surface of FIG. 1;

FIG. 3 is a left side view of the truck exterior surface of FIG. 1;

FIG. 4 is a top view of the truck exterior surface of FIG. 1; FIG. 5 is a bottom view of the truck exterior surface of FIG. 1;

FIG. 6 is a front view of the truck exterior surface of FIG. 1;

FIG. 7 is a back view of the truck exterior surface of FIG. 1;

FIG. 8 is a front perspective view of the second embodiment of a truck exterior surface of the present invention without the optional roof windows, rear sleeper compartment doors and door window of the truck exterior surface of FIG. 1; FIG. 9 is a front view of the truck exterior surface of FIG. 8;

FIG. 10 is a right side view of the truck exterior surface of FIG. 8;

FIG. 11 is the left side view of the truck exterior surface of FIG. 8; and,

FIG. 12 is a top view of the truck exterior surface of FIG. 8, it being understood that the bottom and back views of the truck exterior surface of FIG. 8 are identical to those of the truck exterior surface of the embodiment of FIG. 1. The broken lines shown in all drawing views are for illustrative purposes only and for no part of the claimed design.
